Alfred Oppenhein
ATTORNEY

UNITED STATES PATENT OFFICE

JAMES A. CROTTY, OF NEW YORK, N. Y.

COMBINATION VASE LAMP AND BOUDOIR TRAY

Application filed June 17, 1931. Serial No. 544,975.

This invention relates to combination vase lamp and boudoir tray.

An object of this invention is to provide a combination device of the character described wherein the tray forms part of the vase and when moved into closing position has the appearance of a portion of said vase, with the contents of the tray concealed.

A further object of this invention is to provide a device of the character described having a mirror on the vase portion so positioned that when the tray is swung downwardly or opened for use, the person using cosmetics or the like articles from the tray may directly face the mirror, the construction of the lamp being furthermore such that the light therefrom may most efficiently illuminate the face of the user.

Still another object of this invention is to provide a neat, compact and rugged construction of the character described comprising comparatively few and simple parts, which shall be relatively inexpensive to manufacture, easy to manipulate, and yet practical and efficient to a high degree.

Other objects of this invention will in part be obvious and in part hereinafter pointed out.

The invention accordingly consists in the features of construction, combinations of elements, and arrangement of parts which will be exemplified in the construction herein-after described, and of which the scope of application will be indicated in the following claims.

In the accompanying drawings, in which is shown one of the various possible illustrative embodiments of this invention,

Fig. 1 is an elevational side view of the combination device embodying the invention and showing the article tray swung downwardly in dotted lines;

Fig. 2 is a cross-sectional view taken on line 2—2 of Fig. 1; and

Fig. 3 is a cross-sectional view taken on line 3—3 of Fig. 1.

Referring now in detail to the drawings, 10 designates a combination device embodying the invention here shown in the form of a combination vase lamp and boudoir

tray. Said device 10 comprises a vase 11 on which is mounted a vase or vase simulating member 12 provided with a cover 13. Extending through said cover 13 is a stem or standard 14 carrying electric lamps 15 and a shade 16 surrounding the lamps. The base and vase 12 may be of any ornamental shape, the vase preferably being however, of generally rectangular cross-section. The vase 12 comprises a portion 20 and a portion 21, said portions having vertically mating edge portions or faces 20a and 21a, respectively, and being hinged to one another as at 22 at the bottom of the vase, and together forming a complete vase.

Attached to portion 20 of said vase and adjacent said edge portion 20a is a vertical mirror 24, said mirror obviously being uncovered upon swinging the portion 21 downwardly to the dotted line position of Fig. 1. In said position said portion 21 is adapted to rest on the table or like support on which the base 11 is mounted.

Said portion 21 may be in the form of a boudoir tray and mounted thereon adjacent edge portion 21a is a plate 25, formed with a plurality of openings 26 in which are mounted boxes or containers 27 provided with covers 27a, and adapted to hold various toilet articles such as powder, rouge, lipstick, manicure articles and the like boudoir devices. The covers 27a are preferably fitted frictionally, or in any other suitable manner, to their respective containers, to prevent accidental loosening thereof and for holding the articles within the containers upon closing the tray 21.

It will now be clearly understood that the user need merely swing the tray downwardly and sit in front thereof. The user will then directly face the mirror 24 and the light from the lamps 15 will be thrown on the face of the user, so as to give the most practical and efficient illumination, for example, when applying cosmetics to the face. Any suitable means such as a spring clip or clamp 30 of any suitable construction, may be used for retaining the tray 21 in vertical position. A knob 32 may be slidably mounted on tray portion 21 for releasing the spring 100

clamp. It will be noted that when the tray 21 is in full line position of Fig. 1, it forms part of the vase, thus effectively housing and concealing the containers or boxes 27 and providing a highly attractive article which is nevertheless practical and useful as well. The vase may have beading or ornamentation 33 symmetrically disposed with respect to beading 33a at the split of the vase for 10 camouflaging the split.

It will thus be seen that there is provided a device in which the several objects of this invention are achieved, and which is well adapted to meet the conditions of practical 15 use.

As various possible embodiments might be made of the above invention, and as various changes might be made in the embodiment set forth, it is to be understood that all 20 matter herein set forth or shown in the accompanying drawings is to be interpreted as illustrative and not in a limiting sense.

Having thus described my invention, I claim as new and desire to secure by Letters 25 Patent:

1. In combination, a vase member vertically slit into two sections, hinged together at the bottom of the vase, one of said sections carrying a vertical mirror and the other of 30 said section carrying a plurality of containers, said mirror being adapted to be exposed upon swinging the said second section away from said first section.

2. In combination, a base, a vase mounted 35 thereon and a lamp mounted on said vase, said vase comprising two mating sections and having a mirror on one of said sections, adapted to be exposed upon moving said sections apart.

40 3. In combination, a base, a vase mounted thereon and a lamp mounted on said vase, said vase comprising two mating sections and having a mirror on one of said sections adapted to be exposed upon moving said sections 45 apart, said other section being provided with a plurality of cosmetic containers.

4. A vase, or the like ornamental article, split vertically into two sections hinged together on the bottom of the vase to permit 50 one of said sections to be swung into substantially horizontal position, said last named section being provided with a plurality of containers.

5. A vase or the like ornamental article, 55 split vertically into two sections hinged together at the bottom of the vase to permit one of said sections to be swung into substantially horizontal position, said last named section being provided with a plurality of 60 containers, and a mirror mounted on said other section adapted to be exposed upon swinging said first section to said horizontal position.

6. A vase or the like ornamental article, 65 split vertically into two sections hinged to-

gether at the bottom of the vase to permit one of said sections to be swung into substantially horizontal position, said last named section being provided with a plurality of containers, a mirror mounted on said other section adapted to be exposed upon swinging said first section to said horizontal position, and a lamp mounted on said vase and disposed above said vase adapted to throw light upon the face of a person sitting in front of 70 said first section.

In testimony whereof I affix my signature.

JAMES A. CROTTY.
